**STEREOPHONIC PHONOGRAPH OR
SIMILAR ARTICLE**

George M. Buckler, Baldwinsville, N.Y., assignor to
General Electric Company, a corporation of New
York

Filed Jan. 7, 1966, Ser. No. 523

Term of patent 14 years

(Cl. D56—4)

FIG.1

FIG.2

FIG.3

FIG.4

FIG.5.

FIG.6.

FIG.7

FIG.8

FIG.9

FIG.10

FIGURE 1 is a perspective view of a stereophonic phonograph or similar article showing my new design with the record changer door closed;

FIGURE 2 is a plan view of the phonograph as shown in FIGURE 1;

FIGURE 3 is a front view of the phonograph as shown in FIGURE 1;

FIGURE 4 is a rear view of the phonograph as shown in FIGURE 1;

FIGURE 5 is a left end view of the phonograph as shown in FIGURE 3;

FIGURE 6 is a right end view of the phonograph as shown in FIGURE 3;

FIGURE 7 is a perspective view of the phonograph of FIGURE 1, with the record changer in its operative position;

FIGURE 8 is a left end view of the phonograph for the record changer position shown in FIGURE 7, the right end view being substantially a mirror image thereof;

FIGURE 9 is a plan view of the phonograph as seen in FIGURE 7; and

FIGURE 10 is a fragmentary front view of the phonograph as seen in FIGURE 7.

The dominant features of my new design are shown in solid lines in the drawing.

I claim:

The ornamental design for a stereophonic phonograph or similar article, substantially as shown and described.
